rial No. 112,430. In Germany May 25, 1936

9 Claims. (Cl. 91—68)

This invention relates to methods of producing waterproof air transmissive fabrics for garments.

There is a method already known by means of which fabrics for dressmaking purposes are produced which are extraordinarily light, waterproof and transmissive for air. According to the known method a fine cotton fabric which has been shrunk to a maximum degree by means of a lye-treatment, is then impregnated with an impregnating agent and subsequently subjected to a calendering process.

The object of the present invention is to materially simplify and improve a method of this kind:

It has been found that as starting materials not only shrunk cotton fabrics enter into question but that likewise also non-shrunk cotton fabrics as well as other fibrous textiles are suitable for obtaining the desired result, such as wool, silk, artificial silk or the like, or textiles such as are known under the trade names of "Vistra" which is a mixture of staple fiber with cotton and "Wollstra" which is a mixture of staple fiber with wool. Furthermore, the reducing of the pores by shrinkage by means of an acid treatment can be replaced by providing correspondingly small pores between the individual threads during the weaving. With a view to ascertaining the proper kind of fabric, we have made extensive tests with the result that, for example, for cotton a fabric say of the type 70/70, 40/40 has sufficiently small pores without requiring shrinking. It is to be noted that this mode of designating the fabric corresponds to that which is usual in the weaving industry in that the numerical data 70/70 indicate that the weft as well as the warp threads of the fabric have the number 70, this number 70 defining a thread or yarn a hank length of 70 x 840 yards of which weighs one British pound. The latter data 40/40 indicate that in the warp and in the weft 40 threads are applied per $\frac{1}{4}$ of a French inch. By this designation the fabric will be clearly defined to persons familiar with fabrics. Such a fabric is provided with pores sufficiently small for the present purpose without requiring to be shrunk by means of a lye-treatment.

It is obvious that the hereinafter described impregnating and fixing treatments can be applied also to a cotton fabric the pores of which have been decreased by shrinkage by means of a lye-treatment. At the same time, compared with the methods hitherto used, the impregna-

tion is materially improved in regard to resistivity against water and fastness to washing.

We have further found that fabric impregnated with paraffin solutions or other water-repellent materials is impaired to some extent, 5 when repeatedly washed (say three times).

In order to avoid this drawback the fabric is impregnated with artificial resins, which are dissolved in volatile solvents, following the impregnation with water-repellent materials. These 10 artificial resins are insoluble in water and consequently protect the water-repellent impregnation against being removed by washing. By proportioning the amount of artificial resin incorporated in the fabric by this impregnation the 15 air transmissive properties of the fabric can be varied to a certain extent.

Thus if, for example, 10 grams of artificial resin (solid) dissolved in 100 grams of benzol are applied to 1 square metre of fabric the resulting fabric is appreciably transmissive for air. When, however, the amount of artificial resin applied to the square metre is increased to about 25 grams of artificial resin (solid) dissolved in 100 grams of benzol, a highly waterproof fabric 25 is obtained the air transmissive properties of which are, however, slightly decreased.

For the impregnation several artificial resins are suitable, particularly those that are soluble in benzol, toluol or the like. During our tests we 30 have found that the polymerisation products of vinyl acetate are particularly advantageous. These products are known in the color industry as ingredients for lacquer. According to the present invention for the purpose of applying 35 such products to the waterproofing of textiles the polymerisation products of vinyl acetate are dissolved in benzol or toluol or other volatile solvents. Advantageously, to the solution a small percentage of paraffin oil or else softening agents 40 known per se such as, for example, synthetic esters of a high boiling point are added in order to prevent the layer of artificial resin becoming too brittle after drying. The impregnation is, advantageously, carried out in a trough through 45 which the fabric web is passed via guide rolls in a manner as usual in the textile industry. It may also be suitable to employ means for tensioning the fabric as this is likewise customary in the textile industry.

By effect of this impregnation with artificial resins the water-repellent materials are protected against being washed out, so that the fabric remains waterproof even after repeated washings. We have now found that a fabric impreg- 55

- nated with artificial resins is not fast against being washed out by dipping in water to the same extent as a fabric which has been impregnated, for example, with paraffin emulsions.
- 5 The water does not readily trickle down and off of the fabric which has been simply impregnated with artificial resins. With a view to also obtaining high fastness of the fabric to dipping in water, the fabric may, after the impregnation 10 with artificial resins, be once more impregnated with water-repellent material, particularly with paraffin solutions or emulsions. In this way a thin covering layer of paraffin for the artificial resin is produced which layer renders the fabric 15 fast to dipping in every respect.

The fabric thus impregnated is then subjected to a calendering process. In this connection it has been experienced that it is advantageous to apply low temperatures since at higher temperatures the artificial resins become somewhat viscous. Therefore, the fabrics are calendered at a temperature of approximately 25° C. and at a pressure lower than usual for this purpose.

20 The method steps described above may be singly applied. Alternatively, a mode of procedure may be chosen so that the entirety of method steps herein described is applied. In this case the method is carried out as follows:

25 A fabric composed of any desired fibrous material and having fine pores similar to a cotton fabric 70/70, 40/40 or a cotton fabric the pores of which have been decreased by shrinking it with caustic soda lye, is impregnated with water-repellent material, advantageously with paraffin solutions or paraffin emulsions, and is then dried. Thereupon, the fabric is impregnated with artificial resins, which are dissolved in volatile solvents, so that approximately 10 to 25 grams of artificial resin (solid) are incorporated in every 30 square metre of fabric. As particularly appropriate artificial resins the polymerisation products of vinyl acetate enter into question to the solutions of which paraffin oils are added as softening agents.

35 45 The fabric impregnated with these artificial resins is impregnated once more, after drying, with water-repellent material, for example, paraffin solutions or emulsions and is then calendered at about 25° C. and below the usual pressures applied for this purpose.

We claim:

1. The method of producing lightweight, air-transmissive, waterproof fabric for garments having high resistivity to impairment of its waterproof property from the effects of washing, comprising impregnating a textile fabric having small pores substantially of the size of the pores of a fabric of the type 70/70, 40/40 with liquid paraffin in a quantity insufficient, when dry, to close the pores of the fabric, drying the paraffin to solid state, then impregnating same fabric with from about 10 to 20 grams per square meter of vinyl acetate artificial resin, then calendering the fabric at a temperature of about 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
2. The method of producing lightweight, air-transmissive, waterproof fabric for garments having high resistivity to impairment of its waterproof property from the effects of washing, comprising impregnating a textile fabric having small pores substantially of the size of the pores of a fabric of the type 70/70, 40/40 with liquid paraffin in a quantity insufficient, when dry, to close the pores of the fabric, drying the paraffin to solid state, then impregnating said fabric with from about 10 to 20 grams per square meter of vinyl acetate artificial resin, then calendering the fabric at a temperature of about 25° C., at which temperature the paraffin and resin jointly will not become viscous so as to prevent spreading of the impregnants and closing the pores of the fabric from the effect of calendering.

3. The method of producing lightweight, air-transmissive, waterproof fabric for garments having high resistivity to impairment of its waterproof property from the effects of washing, comprising impregnating a textile fabric having small pores substantially of the size of the pores of a fabric of the type 70/70, 40/40 with liquid paraffin in a quantity insufficient, when dry, to close the pores of the fabric, drying the paraffin to solid state, then impregnating said fabric with a volatile solvent solution of vinyl acetate artificial resin which leaves in the fabric, when dried, from 10 to 25 grams of the resin per square meter of the fabric, drying the resin solution, and calendering the fabric at a temperature of about 25° C., at which temperature the paraffin and resin jointly will not become viscous so as to prevent spreading of the impregnants and closing the pores of the fabric from the effect of calendering.

4. The method of producing lightweight, air-transmissive, waterproof fabric for garments having high resistivity to impairment of its waterproof property from the effects of washing, comprising impregnating a textile fabric having small pores substantially of the size of the pores of a fabric of the type 70/70, 40/40 with liquid paraffin in a quantity insufficient, when dry, to close the pores of the fabric, drying the paraffin to solid state, then impregnating said fabric with a volatile solvent solution of vinyl acetate artificial resin which leaves in the fabric, when dried, from 10 to 25 grams of the resin per square meter of the fabric, drying the resin solution, and calendering the fabric at a temperature of about 25° C., at which temperature the paraffin and resin jointly will not become viscous so as to prevent spreading of the impregnants and closing the pores of the fabric from the effect of calendering.

5. The method of producing lightweight, air-transmissive, waterproof fabric for garments having high resistivity to impairment of its waterproof property from the effects of washing, comprising impregnating a textile fabric having small pores substantially of the size of the pores of a fabric of the type 70/70, 40/40 with liquid paraffin in a quantity insufficient, when dry, to close the pores of the fabric, drying the paraffin to solid state, then impregnating said fabric with from about 10 to 20 grams per square meter of vinyl acetate artificial resin, then calendering the fabric at a temperature of about 25° C., at which temperature the paraffin and resin jointly will not become viscous so as to prevent spreading of the impregnants and closing the pores of the fabric from the effect of calendering.

6. The method of producing lightweight, air-transmissive, waterproof fabric for garments having high resistivity to impairment of its waterproof property from the effects of washing, comprising impregnating a textile fabric having small pores substantially of the size of the pores of a fabric of the type 70/70, 40/40 with liquid paraffin in a quantity insufficient, when dry, to close the pores of the fabric, drying the paraffin to solid state, then impregnating said fabric with from about 10 to 20 grams per square meter of vinyl acetate artificial resin, then calendering the fabric at a temperature of about 25° C., at which temperature the paraffin and resin jointly will not become viscous so as to prevent spreading of the impregnants and closing the pores of the fabric from the effect of calendering.

7. The method of producing lightweight, air-transmissive, waterproof fabric for garments having high resistivity to impairment of its waterproof property from the effects of washing, comprising impregnating a textile fabric having small pores substantially of the size of the pores of a fabric of the type 70/70, 40/40 with liquid paraffin in a quantity insufficient, when dry, to close the pores of the fabric, drying the paraffin to solid state, then impregnating said fabric with a volatile solvent solution of vinyl acetate artificial resin which leaves in the fabric, when dried, from 10 to 25 grams of the resin per square meter of the fabric, drying the resin solution, and calendering the fabric at a temperature of about 25° C., at which temperature the paraffin and resin jointly will not become viscous so as to prevent spreading of the impregnants and closing the pores of the fabric from the effect of calendering.

of a fabric of the type 70/70, 40/40 with liquid paraffin in a quantity insufficient, when dry, to close the pores of the fabric, drying the paraffin to solid state, then impregnating said fabric with 5 from about 10 to 20 grams per square meter of vinyl acetate artificial resin, then calendering the fabric at a temperature of about 25° C. at which temperature the paraffin and resin jointly will not become viscous so as to prevent spreading 10 of the impregnants and closing the pores of the fabric from the effect of calendering.

7. The method of producing lightweight, air-transmissive, waterproof fabric for garments having high resistivity to impairment of its 15 waterproof property from the effects of washing, comprising impregnating a silk textile fabric having small pores substantially of the size of the pores of a fabric of the type 70/70, 40/40 with liquid paraffin in a quantity insufficient, 20 when dry, to close the pores of the fabric, drying the paraffin to solid state, then impregnating said fabric with from about 10 to 20 grams per square meter of vinyl acetate artificial resin, then calendering the fabric at a temperature of about 25° C. at which temperature the paraffin and 25 resin jointly will not become viscous so as to prevent spreading of the impregnants and closing the pores of the fabric from the effect of calendering.

8. The method of producing lightweight, air-transmissive, waterproof fabric for garments having high resistivity to impairment of its waterproof property from the effects of washing, comprising impregnating a textile fabric having small 30

pores substantially of the size of the pores of a fabric of the type 70/70, 40/40 with an emulsion of paraffin in a quantity insufficient, when dry, to close the pores of the fabric, drying the paraffin emulsion to solid state, then impregnating said fabric with from about 10 to 20 grams per square meter of vinyl acetate artificial resin, then calendering the fabric at a temperature of about 25° C., at which temperature the paraffin and resin jointly will not become viscous so as to prevent spreading of the impregnants and closing 10 the pores of the fabric from the effect of calendering.

9. The method of producing lightweight, air-transmissive, waterproof fabric for garments 15 having high resistivity to impairment of its waterproof property from the effects of washing, comprising impregnating a textile fabric having small pores substantially of the size of the pores of a fabric of the type 70/70, 40/40 with a solution of 20 paraffin in a quantity insufficient, when dry, to close the pores of the fabric, drying the paraffin solution to solid state, then impregnating said fabric with from about 10 to 20 grams per square meter of vinyl acetate artificial resin, then 25 calendering the fabric at a temperature of about 25° C., at which temperature the paraffin and resin jointly will not become viscous so as to prevent spreading of the impregnants and closing 30 the pores of the fabric from the effect of calendering.
